CLAIM

The ornamental design for an induction range with oven, as shown and described.

DESCRIPTION

FIG. 1 is a front perspective view of an induction range with oven showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is an enlarged view of the encircled portion 8 in FIG. 1;
FIG. 9 is an enlarged view of the encircled portion 9 in FIG. 1;
FIG. 10 is an enlarged view of the encircled portion 10 in FIG. 2; and,
FIG. 11 is an enlarged view of the encircled portion 11 in FIG. 4.

The evenly-dashed broken lines in the figures depict portions of the induction range with oven that form no part of the claimed design.

The dot-dot-dash broken lines encircling portions of the claimed design that are illustrated in enlargements form no part of the claimed design.

1 Claim, 11 Drawing Sheets
